[57] CLAIM

The ornamental design for an end closure for containers, as shown.

DESCRIPTION

FIG. 1 is a top plan of an end closure for containers showing my new design;

FIG. 2 is a bottom plan view thereof;

FIG. 3 is a side elevational view thereof; and

FIG. 4 is a cross-sectional view thereof, taken in the direction of the arrows along line 4—4 of FIG. 1, the closure being in a position of use.

FIG. 1

FIG. 2
